UNITED STATES PATENT OFFICE.

AUGUST F. ZIMMERLING, OF MILWAUKEE, WISCONSIN, ASSIGNOR OF ONE-HALF TO J. A. DUTCHER AND P. E. DUTCHER, OF SAME PLACE.

GAS-BURNER.

SPECIFICATION forming part of Letters Patent No. 369,421, dated September 6, 1887.

Application filed August 9, 1886. Serial No. 210,487. (No model.)

To all whom it may concern:

Be it known that I, AUGUST F. ZIMMERLING, of Milwaukee, in the county of Milwaukee and State of Wisconsin, have invented 5 new and useful Improvements in Gas-Burners; and I do hereby declare the following to be a full, clear, and exact description of said invention, reference being had to the accompanying drawings, and to the letters or figures of 10 reference marked thereon, which form a part of this specification.

Figure 1 of the accompanying drawings represents a vertical section of my invention; and Figs. 2, 3, and 4 are details.

Like parts are represented by the same reference letters throughout the several views.

A is the combustion-chamber of my burner, into which gas is admitted through the small central opening, B, at the apex of the cone C 20 from the gas-pipe M, while a large volume of air is admitted freely through the open bottom of the chamber A and mingle with the gas in its escape through the flame-openings D.

The neck E of the chamber A is so reduced 25 in size as to contract the stream of the upward-escaping gas, thus increasing the force of its current, whereby a large volume of air is drawn up into the chamber and mingled and consumed with the gas. The opening B is closed by turning down the cap C upon the stationary stop F, and the escape of gas is nicely adjusted to 30 any desired quantity by turning said cap upward or downward upon the screw-threaded thimble G. The stop F is supported in the 35 thimble G upon the cross-bar H, which bar is permanently attached to said thimble.

When the cone C is once properly adjusted to admit the required proportion of gas for the air admitted to produce the desired flame and 40 the most economical results, the cap may be left at rest, and the gas may be turned on and off thereafter by opening and closing the stop-cock I in the pipe.

To facilitate turning the cone C when ad-

justing it, the same is attached to the hand-wheel J. The wheel J serves the twofold purpose of turning the cone C when adjusting it and that of supporting the chamber A, which rests upon it. Upward-projecting lugs K are formed upon the upper edges of the arms of 50 the wheel J, which serves to retain the chamber A in position centrally above the cone C. Knobs L are formed upon the periphery of the wheel J, by which it is turned.

Having thus described my invention, what 55 I claim as new, and desire to secure by Letters Patent, is—

1. In a gas-burner, the combination of the combustion-chamber A, having a series of apertures around its top and an enlarged open 60 bottom, screw-threaded gas tube or thimble G, rigidly affixed to the gas-pipe M, gas-pipe M, screw-threaded cone C, fitted upon the screw-threaded surface of the thimble G and provided with an aperture at its apex, stop F, fitted to 65 the aperture in said cone C, and hand-wheel J, affixed to said cone C and supporting said chamber A centrally above said cone, substantially as and for the purpose set forth.

2. The combination of the stationary screw-threaded thimble G, stop F, rigidly affixed to the interior walls of said thimble, screw-threaded cone C, fitted to said thimble G, hand-wheel J, affixed to the cone C, and combustion-chamber A, supported above said 75 cone C upon said hand-wheel A, substantially as shown and described.

3. The combination of the screw-threaded thimble G, stop F, screw-threaded cone C, hand-wheel J, chamber A, gas-pipe M, and 80 stop-cock I, substantially as and for the purpose specified.

In testimony whereof I affix my signature in presence of two witnesses.

AUGUST F. ZIMMERLING.
